(57) **CLAIM**

The ornamental design for a work light, as shown and described.

DESCRIPTION

FIG. 1 is a front view of a work light showing my new design.

FIG. 2 is a rear view of the work light.

FIG. 3 is a right view of the work light.

FIG. 4 is a left view of the work light.

FIG. 5 is a top view of the work light.

FIG. 6 is a bottom view of the work light.

FIG. 7 is a perspective view of the work light.

FIG. 8 is another perspective view of the work light.

FIG. 9 is a perspective view of the work light, illustrating a hanger of a light body at an upward unfolded position.

FIG. 10 is a perspective view of the work light, illustrating a light base rotatably coupled with the light body.

FIG. 11 is a front view of the light base of the work light, shown separately for ease of illustration.

FIG. 12 is a rear view of the light base of the work light.

FIG. 13 is a right view of the light base of the work light.

FIG. 14 is a left view of the light base of the work light, wherein the broken lines in FIG. 14 are included for the purpose of illustrating a portion of light base that forms no part of the claimed design.

FIG. 15 is a top view of the light base of the work light.

FIG. 16 is a bottom view of the light base of the work light.

FIG. 17 is a perspective view of the light base of the work light.

FIG. 18 is a perspective view of the light base of the work light, illustrating a light base at an open position.

FIG. 19 is a front view of the light body of the work light, shown separately for ease of illustration.

FIG. 20 is a rear view of the light body of the work light.

FIG. 21 is a right view of the light body of the work light.

FIG. 22 is a left view of the light body of the work light.

FIG. 23 is a top view of the light body of the work light.

FIG. 24 is a bottom view of the light body of the work light.

FIG. 25 is a perspective view of the light body of the work light.

FIG. 26 is another perspective view of the light body of the work light.

FIG. 27 is a perspective view of a light base holder of the work light, illustrating the light body coupled with a light body holder.

FIG. 28 is a front view of the light base holder of the work light, shown separately for ease of illustration.

FIG. 29 is a rear view of the light base holder of the work light.

FIG. 30 is a right view of the light base holder of the work light.

FIG. 31 is a left view of the light base holder of the work light.

FIG. 32 is a top view of the light base holder of the work light.

FIG. 33 is a bottom view of the light base holder of the work light; and,

FIG. 34 is a perspective view of the light base holder of the work light.
